(57) **CLAIM**

The ornamental design for a micrometer, as shown and described.

DESCRIPTION

[FIG. 1 is an upper perspective view of an exemplary micrometer;]

[FIG. 2 is a front view of the micrometer;]

[FIG. 3 is a rear view of the micrometer;]

[FIG. 4 is a bottom view of the micrometer;]

[FIG. 5 is a top view of the micrometer;]

[FIG. 6 is a left side view of the micrometer;]

[FIG. 7 is a front view of another exemplary micrometer, with the other views the same as shown above in connection with FIG. 1; and,]

[FIG. 8 is a front view of still another exemplary micrometer, with the other view the same as shown above in connection with FIG. 1.]

FIG. 9 is a top and front perspective view of a micrometer;

FIG. 10 is a front elevation view of the micrometer;

FIG. 11 is a rear elevation view of the micrometer;

FIG. 12 is a left side elevation view of the micrometer;

FIG. 13 is a top plan view of the micrometer; and,

FIG. 14 is a bottom plan view of the micrometer.

1 Claim, 14 Drawing Sheets

Matter enclosed in heavy brackets [ ] appears in the original patent but forms no part of this reissue; matter printed in italics indicates the additions made by reissue.
